UNITED STATES PATENT OFFICE.

WILLIAM ERWIN, OF PHILADELPHIA, PENNSYLVANIA.

INTERNAL-EXPLOSION ENGINE.

1,213,172.

Specification of Letters Patent. Patented Jan. 23, 1917.

Application filed March 29, 1916. Serial No. 87,468.

To all whom it may concern:

Be it known that I, WILLIAM ERWIN, a citizen of the United States, residing at No. 4844 Cedar avenue, in the city of Philadelphia, in the county of Philadelphia and State of Pennsylvania, have invented a new and useful internal-explosion engine of extreme simplicity, with a remarkably small number of moving parts having an exclusive 10 and constant rotary motion, economy of power by turbine application, silence in operation, and avoidance of either a hand or a power starting device, especially designed for automobile power equipment, but equally 15 suitable for any light or medium powered portable or stationary engine, of which a clear and accurate description is presented by the following specification and drawings, which form a part of it.

20 Figure 1, is a left side view of the engine, with the left side and lower part of the generator casing broken away, and the turbine and pressure chamber shown in central vertical section; Fig. 2, is a plan view 25 of the automatically reversing pedals which control the engine feed valve; Fig. 3, is a horizontal sectional view of the generator upon the line of its main shaft, seen from above; Fig. 4, is a rear view of the generator, with the rear part of its casing broken away, and a part of the supporting bracket of its main shaft also broken away; Fig. 5, is a vertical sectional view of the generator upon line 45 in Fig. 3, seen from the left; 30 Fig. 6, is a vertical section of a fragment of the generator upon line 46 in Fig. 3, seen from the left; Fig. 7, is a crank used to start the generator by hand to obtain an initial pressure in the pressure chamber.

35 This engine consists of five essential parts, the pressure generator 1, the pressure chamber or reservoir 2, the turbine 3 which is operated by the pressure in chamber 2, the automatically reversing pedals 31 and 32 40 which control valve 30 and the flow of pressure from chamber 2 to turbine 3, and the automatically acting adjustable mechanism which controls the driving gears of generator shaft 9. Pressure chamber 2 having exactly 45 the same function as the steam chest of a steam engine, may actuate the piston of a reciprocating engine as easily and perfectly as the turbine of a rotary engine. As shown in the drawings, generator 1 and turbine 3 are best built integrally with appropriate walls of chamber 2.

This engine differs from all other internal combustion or explosion engines by using as its motive power an explosive solid, such for example as cordite, as distinguished from 60 an explosive liquid, or explosive vapor, or explosive gas.

The cordite is wound upon an axle 4 to form a reel 5, which is suitably placed in generator 1, and its free end is fed by rollers 6 and 7 to eccentrically curved divider 8, which is fixed upon or integral with generator shaft 9, and at each revolution separates from the free end of the cordite each individual charge for explosion, and carries it to a position opposite spark plugs 10 and 11, a hot spark being timed by circuit 12 to pass directly from one spark plug to the other and explode the cordite at this juncture. The resulting gases pass by their own 75 pressure through passages 13 and 14 to the bottom of vessel 15, within pressure chamber 2, which contains a washing liquid, through which the gases pass upward through sieves 16 to still further divide the 80 gas bubbles to complete the washing, and thence into pressure chamber 2.

Power shaft 17, of turbine 3, passes directly through pressure chamber 2, from which it is separated by sleeve 18. Worm 19 85 on sleeve 20, upon power shaft 17, behind pressure chamber 2, drives worm gear 21, which is loose upon generator shaft 9. Worm gear 21 drives wheel 22 by a pawl and ratchet gear, and wheel 22 drives shaft 9, 90 being fixed upon it. Worm 23 upon shaft 9 drives crown worm gear 24, the shaft of which is roller 6. Gear 25 upon the front end of roller shaft 6 meshing with gear 26 upon roller 7, turns the latter toward 6 to 95 carry the free end of the cordite to divider 8. Without disturbing worm gear 21, an initial pressure may be obtained in pressure chamber 2 by giving a few turns to generator shaft 9 with crank 27, rectangular lug 100 28 of which fits into a corresponding recess 29 in the outer end of shaft 9, after which the operation of the entire mechanism becomes automatic, and may be started or stopped by opening or closing turbine feed valve 30 by pressing forward pedals 31 or 32 respectively, the pedals reversing automatically.

The motive power of the generator, derived from shaft 17, is automatically controlled by the pressure in chamber 2, by said pressure acting upon piston 34, spring 110

35, lever 36, and clutch 37, one member of which is fixed upon shaft 17, and the other member is slidingly geared to sleeve 20. A lowered pressure in chamber 2 allows 5 spring 35 to press piston 34 farther into it, which causes lever 36 to engage clutch 37 and thus operate the generator when the engine is running. An unduly raised pressure in chamber 2 will overcome spring 35, push 10 piston 34 outward and cause lever 36 to disengage clutch 37, thus stopping the generator.

An overcharge of pressure in chamber 2 will push piston 34 outward and escape 15 through vent 38 in the wall of chamber 2. The working pressure in chamber 2, indicated by gage 33 upon its wall, is adjustable by regulating the pressure of spring 35, by screwing cap 39 toward the spring for a 20 higher pressure, or by screwing it away from the spring for a lower pressure.

The speed of the gears which operate the generator is so proportioned that the generator will be in continuous operation when 25 the engine is running at highest speed with heaviest load, and will automatically operate intermittently at lower engine speed or load to keep the pressure in chamber 2 at the predetermined degree. Exhaust chamber 40 and exhaust pipe 41 receive and deliver the 30 exhaust gases to a convenient part of the machine.

A part of the gases resulting from the successive explosions in generator 1 leak backward 35 around divider 8, and thus maintain in the generator a pressure equal to that in chamber 2. When a fresh reel of cordite is needed, screw-bolt 42 is turned inward by handle 43 as far as it will go, thus closing 40 passage 13, retaining the pressure in chamber 2, and also opening by-pass 44, which allows escape of pressure in generator 1 around the narrow stem of screw-bolt 42. This by-pass also prevents damage by possible 45 hand operation of the generator when passage 13 is closed by screw-bolt 42. After the new reel of cordite has been placed in the generator, screw-bolt 42 is turned outward as far as it will go, thus closing by- 50 pass 44 and opening passage 13. Valve 47 in chamber 2 allows the inflation of pneumatic vehicle tires by flow of pressure from chamber 2 through a connecting tube to the tires. The outer bracket supporting 55 shaft 9, also supports a rotary circuit breaker, which is operated by shaft 9. Upon the inner surface of circle 48, which is made of insulating material, are three plates 49, two of them conducting plates forming part 60 of the sparking circuit, and all three separated from each other by diagonal inter-spaces 50, the circuit being made and broken by conducting roller 51 carried by shaft 9. Manhole 52 permits access to the interior of 65 chamber 2.

Having described my invention, what I claim as new, and desire to secure by Letters Patent, is—

1. In an explosion engine or motor, a power generator, whose moving parts have a constant rotary motion, for containing and exploding an explosive solid, comprising the combination of a power generator chamber, a reel therein to support said explosive solid, rollers for feeding said explosive for explosion, a rotary divider for separating the individual charges for explosion and delivering them to the path of a sparking or exploding circuit, a sparking or exploding circuit which delivers its spark between two spark plugs, and a rotary circuit breaker operated by the generator shaft for timing the exploding spark.

2. In an explosion engine or motor, the combination of a power generator, whose moving parts have a constant rotary motion, for containing and exploding an explosive solid, with a pressure power chamber for storing the resulting gases, and for delivering them to the motor of the engine.

3. In an explosion engine or motor, the combination of a power generator, whose moving parts have a constant rotary motion, for containing and exploding an explosive solid, means for exploding said explosive solid in the generator, and a pressure power chamber for storing the resulting gases, and for delivering them to the motor of the engine.

4. In an explosion engine or motor, the combination of a rotary power generator for containing and exploding an explosive solid, means for exploding said explosive solid in the generator, a pressure power chamber for storing the resulting gases and delivering them to the motor of the engine, and generator operating gears automatically disconnected by excess pressure in said pressure chamber, said gears being adjustable to operate at various pressures.

5. In an explosion engine or motor, the combination of a rotary power generator for containing and exploding an explosive solid, means for exploding said explosive solid in the generator, a pressure power chamber for storing the resulting gases and delivering them to the motor of the engine, generator operating gears automatically disconnected by excess pressure in said pressure chamber, said gears being adjustable to operate at various pressures, and a fluid pressure turbine or rotary motor operated by the pressure in said pressure chamber.

6. In an explosion engine or motor, the combination of a pressure storage power chamber, a rotary power generator integral with a wall of said chamber for containing and exploding an explosive solid and delivering the resulting gases to said chamber, means for exploding said explosive solid in

the generator, a fluid pressure turbine or rotary motor integral with another wall of said chamber operated by the pressure in said chamber, a valve in the same wall of 5 said chamber admitting its pressure to said turbine or rotary motor, and automatically reversing pedals controlling said valve.

7. In an explosion engine or motor, the combination with a pressure storage power 10 chamber, of a pressure relief vent in a wall of said chamber, a piston within said chamber covering said relief vent until overcome and moved away from it by excessive pressure within said chamber, a rotary power 15 generator integral with another wall of said chamber for containing and exploding an explosive solid and delivering the resulting gases to said chamber, means for exploding said explosive solid in said generator, a gear shifting lever operated by 20 said piston, generator driving gears upon the power shaft of said engine or motor moved by said shifting lever out of operative position by excess pressure upon said 25 piston, and an adjustable spring resisting said piston and moving the piston over said vent, and moving the gear shifting lever and the generator driving gears into operative position upon reduction of pressure 30 within said chamber.

8. In an explosion engine or motor, the combination of a pressure storage power chamber, a rotary power generator integral with a wall of said chamber for containing 35 and exploding an explosive solid, means for exploding said explosive solid in said generator and delivering the resulting gases to said chamber, a vessel contained in said chamber, a washing liquid contained in said 40 vessel for washing said gases upon their passage from the generator through the liquid into said chamber, and a turbine or rotary motor integral with another wall of said chamber operated by the fluid pressure 45 within said chamber and operating said generator.

9. In an engine or motor operated from a chamber containing a fluid pressure, an automatic feeding device for said chamber, 50 adjustable to operate at various pressures within said chamber, comprising the combination with said chamber of a generator integral with one of its walls for containing and exploding an explosive solid and 55 delivering the resulting gases to said chamber, means for exploding said explosive solid in said generator, a screw-bolt for retaining the pressure in said chamber, a bypass for releasing the pressure in said gen-

erator, a piston contained within said chamber actuated by excess pressure therein, a gear shifting lever operated by said piston, generator driving gears upon the power shaft of said engine or motor moved by said shifting lever out of operative position 60 by excess pressure within said chamber upon said piston, and an adjustable spring resisting said piston and moving the piston, the gear shifting lever and the generator driving gears into operative position 65 upon reduction of pressure within said chamber.

10. In an engine or motor operated from a chamber containing a fluid pressure, the combination with said chamber of a rotary 70 power generator integral with a wall of said chamber for containing and exploding an explosive solid and delivering the resulting gases to said chamber, means for exploding said explosive solid in the generator, a pressure relief vent in another wall of said chamber, a piston within said chamber covering said vent and moved away from it by excessive pressure in said chamber, an adjustable spring within said chamber returning said piston to cover said vent upon reduction of pressure in said chamber, and a valve in still another wall of said chamber allowing a flow of its fluid pressure 80 into the pneumatic tires of a vehicle for 85 their inflation or for such like use.

11. In an engine or motor operated from a chamber containing a fluid pressure, the combination of a rotary power generator integral with a wall of said chamber for 90 containing and exploding an explosive solid and delivering the resulting gases into said chamber, means for exploding said explosive solid in said generator, generator driving gears upon the power shaft of said engine or motor, a piston within said chamber actuated by excess pressure therein, a gear shifting lever operated by said piston to move the generator driving gears out of 95 operative position by excess pressure in said chamber, and an adjustable spring resisting said piston and moving said generator driving gears into operative position by reversing said gear shifting lever upon reduction 100 of pressure in said chamber.

In testimony whereof I have signed my name to this specification in the presence of two subscribing witnesses.

WILLIAM ERWIN.
